UNITED STATES PATENT OFFICE.

CHARLES E. WAREAM AND GEORGE N. LINK, OF CINCINNATI, OHIO, ASSIGNEES TO THE AMERICAN LAUNDRY MACHINERY COMPANY, OF CINCINNATI, OHIO, A CORPORATION OF OHIO.

PRESSING-MACHINE.

1,385,057.

Specification of Letters Patent. Patented July 19, 1921.

Application filed June 18, 1919. Serial No. 305,048.

To all whom it may concern:

Be it known that we, CHARLES E. WAREAM and GEORGE N. LINK, citizens of the United States, residing at Cincinnati, in the county of Hamilton and State of Ohio, have invented certain new and useful Improvements in Pressing-Machines, of which the following is a specification.

This invention relates to pressing machines, and more particularly to small presses for pressing collars, cuffs, shirt neckbands, and the like.

The object of the invention is to provide an improved frame construction which simplifies the circulation of steam or heating fluid to the pressing or other members to be heated.

More particularly the invention has for its object to provide a pressing machine frame made in several parts provided with channels or passages so disposed as to register with each other when the parts of the frame are assembled, whereby the frame is simple to construct and provides proper steam circulation at minimum cost.

Further objects of the invention are in part obvious and in part will appear more in detail hereinafter.

The invention comprises the construction and arrangement of parts hereinafter described and claimed.

In the drawings, which represent one suitable embodiment of the invention, Figure 1 is a front view of the upper portion of the machine; Fig. 2 is a side elevation, partly in section on the line 2—2, Fig. 1; Fig. 3 is a side elevation of the lower portion of the machine; Fig. 4 is a sectional elevation, on a larger scale, on the line 4—4, Fig. 1; Fig. 5 is a front view of the lower pressing member or bed; Fig. 6 is a bottom plan view thereof; Fig. 7 is a side elevation from the right in Fig. 5; Fig. 8 is a front view of the upper frame member; Fig. 9 is a side elevation from the right in Fig. 8; Fig. 10 is a bottom plan view thereof; Fig. 11 is a detail cross sectional view on the line 11—11, Fig. 10; Fig. 12 is a front view of the intermediate frame member; Fig. 13 is a plan view thereof; and Fig. 14 is a side elevation from the right in Fig. 12.

The pressing machine shown in the drawings comprises a suitable frame including a stationary base or lower member 1 adapted to rest upon the floor or other suitable support, an intermediate member 2 supported

thereby, and an upper member or head 3 which forms the upper or stationary pressing member. In said frame is mounted a vertically movable lower pressing member 60 or bed 4 which coöperates with the head and is mounted on the upper end of a post 5 to which is connected the operating means for producing vertical movement. Briefly described, the operating mechanism includes 65 a foot treadle 6 pivoted in the machine base and one arm of which, marked 7, coöperates as a toggle with a link 8 connected to the lower end of the post 5. 9 represents the usual release treadle and 10 a compression 70 spring serving as a shock absorber for the descending bed. The bed is provided with a horizontally movable work holding frame 11 provided with the operating handle 12 and also with a rearwardly extending rod 13 75 connected at its outer end to a long link 14 which at its lower end is connected by a short link 15 to the stationary frame. 16 indicates a tension spring normally tending to advance the work holding frame into 80 its outer or exposed position. 16^a is a post on the vertically movable bed, which post is guided in an opening in the stationary frame, as will appear.

The lower frame member or base 1 is 85 provided at its upper end with separated arms or posts 17 whose upper end portions are provided with finished surfaces in a horizontal plane. On these surfaces are supported the intermediate frame member 2 before referred to. This member is illustrated in detail in Figs. 12 to 14 inclusive. It comprises a horizontally extending hollow body 18 provided at its center with an upwardly extending cylindrical portion 19 and at one 90 side thereof with a perforated ear 20 to receive post 16^a. At each end the body is provided with a vertically extending post portion 21 having horizontally finished upper and lower surfaces as shown in Fig. 12. 100 Each of these post portions is provided with a vertically extending through aperture 22 and with a hollow chamber 23 provided with a threaded inlet 24 to receive a pipe or fitting and with an upwardly extending 105 threaded opening 25 communicating with said chamber. The chambers 23 in the two posts 21 communicate with a longitudinally extending hollow passage 26 in the body, said passage in turn communicating with 110 the hollow chamber 27 in the cylinder 19.

The head 3 is of arched form, as shown

in Fig. 8, so that its under surface, which is shaped complementary to the shape of the work holder and bed 4, gives the proper shape to the articles being pressed. Said 5 head has an intermediate hollow body 28 whose inner channel or passage 29 communicates at each end with a chamber 30 in the hollow post portion 31 at the end of said body. This post portion is provided with 10 a vertically extending through opening 32 and at one side thereof with a similar opening 33 passing through the chamber 30, as shown in Fig. 4. Near its center the body 28 is also provided with a threaded passage 15 34 into which may be threaded a pipe or fitting 35.

The frame parts are shown assembled in Figs. 1 and 4. Between the post portions of the frame members 2 and 3 are located 20 suitable gaskets 36, and said frame parts are solidly secured together and to the frame base 1 by the through bolt 37 fastened to the base 1 and provided on its upper end with the clamping nut 38. This bolt passes 25 through the registering openings 22, 32. In the assembled position of the parts the channels 25, 33 register, and communication between chambers 23 and 30 is established 30 through a longitudinal passage 39 and radial ports 40 in a hollow stud 41 threaded into the passage 25. This stud is threaded at its upper end to receive the clamping nut 42, the joint being sealed by a packing 42^a surrounding said stud and lying above a 35 packing nut 42^b.

Steam circulation through the frame may be established in either of two ways. First, the opening 34 in the head may be closed by a plug. In this case steam is supplied 40 through a pipe 43 threaded into one of the passages 24 and flows to the chamber 23. From this chamber the steam flows along two paths, one through the passage 26 and chamber 27 to the chamber 23 in the opposite 45 site post member 21, and the other through the hollow stud 41 to chamber 30, thence through the passage 29 of the head to the other chamber 30 and down through the second hollow stud to the chamber 23 on the 50 other side of the machine, from which it is discharged through a pipe 44. If desired, however, steam circulation may be established from the head downwardly. In other words, steam is supplied through the pipe 55 35 to the center of the head where the current divides and flows toward both sides of the machine thence downwardly through the hollow posts and out through both of the pipes 43, 44. No steam flows through the 60 passage 26 or chamber 27 but they are filled with live steam and maintain the parts hot.

The head of the machine is heated by direct flow of steam therethrough. The bed 4 is a vertically movable member and no steam

is directly supplied thereto. However, said 65 bed has a cylindrical portion 45 which surrounds the cylinder 19, the lower portion of said member 45 being bifurcated, as shown in Fig. 7, to form two arms 46 which straddle the body 18. The bed is therefore heated 70 by contact with the heated cylinder 19, from which the heat is radiated to the cylinder 45.

The machine described is of simple construction since the passages and chambers can be cored out in the castings. By subsequently finishing off the meeting surfaces 75 the course of circulation of the steam is established when the frame parts are secured together.

What we claim is:—

1. A pressing machine, comprising a hollow pressing member, a coöperating presser, said pressing member and presser being relatively movable, a hollow heating member therefor, and means for securing said members together, said means also providing communication between the chambers of 85 said hollow members.

2. A pressing machine, comprising a hollow stationary pressing member, a coöperating movable presser, a hollow heating member therefor, and means for securing said members together, said means also establishing communication between the chambers of 90 said hollow members.

3. A pressing machine, comprising a hollow stationary pressing member, a coöperating movable presser, a hollow heating member therefor, and a hollow bolt passing through one of said members and threaded into the other thereof, the passage through 100 said bolt establishing communication between the chambers of said hollow members.

4. A pressing machine, comprising a hollow stationary pressing member, a coöperating movable presser, a hollow heating member therefor, means for securing said members together, said means also establishing communication between the chambers of 105 said hollow members, and additional means 110 passing through said members for binding them together.

5. A pressing machine, comprising a hollow stationary pressing member, a coöperating movable presser, a hollow heating member therefor, a hollow bolt passing through one of said members and threaded into the other thereof, the passage through 115 said bolt establishing communication between the chambers of said hollow members, and additional means passing through said members for binding them together.

6. A pressing machine, comprising a hollow stationary pressing member, a coöperating movable presser, a hollow heating member therefor, means for securing said members together, said means also establishing communication between the chambers of 120 125

said hollow members, a support for said members, and means carried by said support and engaging said members for binding them together.

5 7. A pressing machine, comprising a hollow stationary pressing member, a coöperating movable presser, a hollow heating member therefor, a hollow bolt passing through one of said members and threaded 10 into the other thereof, the passage through said bolt establishing communication between the chambers of said hollow members, a support for said members, and means carried by said support and engaging said 15 members for binding them together.

8. A pressing machine, comprising a hollow stationary pressing member, a coöperating movable presser, a stationary hollow heating member therefor, a support for said 20 members and means carried by said support and engaging said members for securing them together.

9. A pressing machine, comprising a hollow stationary pressing member having separated post portions, a coöperating movable presser, a hollow heating member therefor having separated post portions, said members being provided in their post portions with registering openings establishing 30 communication between the chambers therein.

10. A pressing machine, comprising a hollow stationary pressing member having separated post portions, a coöperating movable presser, a hollow heating member therefor 35 having separated post portions, said members being provided in their post portions with registering openings establishing communication between the chambers therein, and a securing bolt passing through said 40 openings.

11. A pressing machine, comprising a support having spaced post members, a hollow heating member having post portions seated thereon, a movable presser heated thereby, 45 and a hollow stationary pressing member having post portions seated upon said first named post portions.

12. A pressing machine, comprising a support having spaced post members, a hollow heating member having post portions seated thereon, a movable presser heated thereby, a hollow stationary pressing mem-

ber having post portions seated upon said first named post portions, and means for circulating a heating medium through said 55 post portions.

13. A pressing machine, comprising a support having spaced post members, a hollow heating member having post portions seated thereon, a movable presser heated thereby, 60 a hollow stationary pressing member having post portions seated upon said first named post portions, and a hollow bolt passing through said post portions for establishing communication between the chambers of said 65 hollow members.

14. A pressing machine, comprising a support having spaced post members, a hollow heating member having post portions seated thereon, a movable presser heated thereby, 70 a hollow stationary pressing member having post portions seated upon said first named post portions, means for circulating a heating medium through said post portions, and a bolt carried by each of said post members 75 and engaging said post portions for securing them together.

15. A pressing machine, comprising a support having spaced post members, a hollow heating member having post portions seated 80 thereon, a movable presser heated thereby, a hollow stationary pressing member having post portions seated upon said first named post portions, a hollow bolt passing through said post portions for establishing communication between the chambers of said hollow 85 members, and a bolt carried by each of said post members and engaging said post portions for securing them together.

16. A pressing machine, comprising a 90 frame having chambered pressing and heat radiating portions immovable relative to each other and having inner channels providing communication within the frame between the chambers, means for circulating 95 heating medium through said chambers and channels, and a pressing member heated by said radiating portion and coöperatively movable relative to the pressing portion of said frame.

In testimony whereof we affix our signatures.

CHARLES E. WAREAM.
GEORGE N. LINK.
